UNITED STATES PATENT OFFICE.

HUGH McCABE, OF LAWRENCE, MASSACHUSETTS.

FLANGING MACHINE.

Application filed June 2, 1920. Serial No. 385,885.

To all whom it may concern:

Be it known that I, HUGH McCABE, a citizen of the United States, residing at Lawrence, in the county of Essex and State of Massachusetts, have invented certain new and useful Improvements in Flanging Machines; and I do hereby declare the following to be a full, clear, and exact description of the invention, such as will enable others skilled in the art to which it appertains to make and use the same.

This invention relates to a flanging machine, and more particularly to a flanging machine of the type disclosed in the patent to Hugh McCabe No. 1,030,416, dated June 25, 1912, upon which the present invention is an improvement.

The flanging machine disclosed in the above mentioned patent operates to form a flange by bending the material step by step. During each step, successive adjacent increments of the flange are bent through a part of the angle to which it is desired to bend the same to form the completed flange. The flange is bent down by the engagement of a bender with successive adjacent portions of the flange, the bender being oscillated repeatedly through the same angle, and the completed flange is formed preferably in three successive steps.

In forming flanges on metal plates, and particularly on plates having any degree of resiliency, the flange springs back somewhat after it is bent by the bender. For example, when the first increment of the flange is bent down through an angle of, say, 40°, and the bender is released, the flange springs back somewhat so that it does not occupy a position corresponding to an angle of 40°, but, on the contrary, occupies a position corresponding to an angle somewhat less than 40°. Inasmuch as the work is fed laterally through the machine after each oscillation of the bender, it will be apparent that this spring back of the metal interferes with the feeding of the work through the machine. It is important therefore that after the initial increment of the second and third steps of the flanging operation provision be made for positioning the arc of oscillation of the bender to return the latter sufficiently so that it will be clear of the flange allowing for the spring back of the latter. In the above mentioned patent, a mechanism is disclosed

and claimed for accomplishing this result.

The mechanism for positioning the arc of oscillation of the bender disclosed in the above mentioned patent includes a dog 500 mounted upon a collar 410 secured upon a rod 390. The dog 500 is adapted to be moved down into the path of a collar 380 carried by the end of the rack 250 and through which the rod 390 is extended, so as to be engaged by the collar 380 upon the return movement of the rack. The dog 500 is normally held in a raised position by a coiled spring 510, the construction and arrangement of which is illustrated in Fig. 7 of the patent. Provision is made for automatically moving the dog 500 down into the path of the collar 380 whenever the rack is disengaged in the operation of re-positioning it with relation to the bender segment 240 in order to advance the bender through the successive steps of the flanging operation. For this purpose the heel of the dog 500 is provided with a lug 501 adapted to be struck by a stop lug 502 extended from the machine frame as the lug 501 moves downwardly when the rack is swung down and out of engagement with the bender segment to thereby cause the dog to swing about its pivot and down into a position in the path of the collar 380. The dog 500 may be manually moved into its lowered position by means of a handle 514. When the handle 514 is swung to the left, viewing Fig. 1, the yoke 509 is moved to the left thereby releasing the compression on the coiled spring 510 and permitting the weight of the dog to move it down. With the handle in this position the dog will remain in its lowered position until the handle is again swung to the right.

The operation of the mechanism is as follows: The normal extent of rack movement is such as to oscillate the bender through an angle approximately 40°, which produces a net advance of the flange through an angle somewhat less than 40° because of the spring back of the flange. This angle is slightly greater than 30°. The first step of flange bending is secured by repeated oscillations of the bender through its normal arc across the entire length of the work. After the last increment of the flange of this first step has been bent down and the rack is in its extended position, the handle 290 is swung to the right, thereby disengaging the rack from

the bender segment and at the same time causing the dog 500 to be lowered into the path of the collar 380 by the engagement of the lug 501 with the stop 502. The rack is then run back until the collar 380 strikes the dog 500 and operates to move the rod 390 to the right and thereby shut off the supply of air to the cylinder 270. The rack is then re-engaged with the bender segment and again 10 run forward causing the initial oscillation of the bender of the second step of the flanging operation through an arc of approximately 30°. When the rack is re-engaged, the coiled spring 510 (the handle 514 being 15 in its extreme position to the right) operates to immediately lift the dog 500 out of the path of the collar 380. When, therefore, the rack is again run back after the initial downward stroke of the bender upon the 20 second step of the flanging operation, the collar 380 passes under the dog 500 and the bender is returned approximately 10° clear of the flange. The second step of the flanging operation from this point is carried on 25 in the usual manner by repeated oscillations of the bender through an angle of approximately 40° and thereby advancing the flange through an angle which approximates 30°. In this manner the normal arc of oscillation 30 of the bender is positioned so as to enable the work to be freely fed through the machine. After the last increment of the second step of the flange has been turned down the rack 250 is in an extended position and 35 is now disengaged from the bender segment by the handle 290 which again operates to automatically lower the dog 500 in the path of the collar 380. The rack is then run back (while disengaged) until the collar 380 40 strikes the dog 500 and thereby cuts off further movement of the rack. At this point the rack is re-engaged and the initial increment of the last step of the flange is turned down through an angle of approximately 45 30°. The dog 500 is immediately raised by the action of the spring 510 so that when the rack is run back the collar 380 passes under the dog and the bender is returned clear of the flange. The third step of the flanging 50 operation is now carried on until the last increment of the third step has been turned down, thus forming a completed flange (after the flange has sprung back) of substantially 90°. 55 In order to reposition the rack with relation to the bender segment so as to return the bender to its initial starting point, the handle 514 is swung to the left, thereby lowering the dog 500 into the path of the collar 380. It will be observed that the dog 500 will be maintained in its lowered position until the handle 514 is manually swung to the right again. With this in mind the rack 60 is run back from its extended position without being disengaged from the bender 65

segment until the collar 380 strikes the dog 500. This returns the bender approximately 30°. The rack is then disengaged, run forward, re-engaged, and then run back, returning the bender through a second angle 70 of approximately 30° being stopped when the collar 380 strikes the dog 500. The rack is now disengaged, run forward, re-engaged and run back. At any time after the rack has been re-engaged for the second time, the 75 handle 514 is swung to the right, thereby lifting the dog 500 so that the collar 380 is permitted to pass beneath the dog as the rack is run back and the bender is thereby returned through a final angle of approximately 80 40° and to its initial position. While this construction operates successfully, it has been found to be too delicate and frail for use by the class of labor which is usually 85 employed to operate flanging machines of this type with the result that the mechanism is more or less easily broken and the continuous operation of the machine interfered with.

The object of the present invention is to 90 provide a flanging machine of the type mentioned with an improved device for positioning the normal arc of oscillation of the bender to enable the work to be fed freely through the machine. The improved device is of strong and substantial construction, capable of withstanding abuse and accomplishes the desired object in a positive and superior manner.

The invention consists in the flanging machine hereinafter described and particularly defined in the claims.

In the drawings in which the preferred embodiment of the invention is illustrated, Figure 1 is a side elevation of the flanging machine; Fig. 2 is an enlarged side elevation of the compensating device in its locked position; Fig. 3 is a plan of the left hand end of the device shown in Fig. 2 in its inoperative or normal position; and Fig. 4 is a side elevation of the right hand end of the device shown in Fig. 2 in its inoperative or normal position.

The construction and operation of the flanging machine is in general the same as 115 that disclosed and fully described in the above mentioned McCabe Patent No. 1,030,416, to which reference may be had.

The improved device for positioning the 120 arc of oscillation of the bender to enable the work to be fed freely through the machine is described as follows: The body portion 51 of the improved positioning device is loosely mounted upon the rod 390 and is held from movement longitudinally of the 125 rod in one direction by a stop collar 52 secured upon the rod by a set screw 53 and in the other direction by a second stop 54 also secured upon the rod 390. A compression and torsion coil spring 55 serves by 130

expansion longitudinally to yieldingly hold the end of the body portion 51 against the stop collar 52 and also torsionally to yieldingly hold the body portion in an inoperative position. One end of the body portion 51 is cut away to form an engaging nose 61 offset from the rod 390 a sufficient distance to permit passage of the collar 380 by the nose whenever the device is in its inoperative position, such as is shown in plan in Fig. 3. A chain 60 is attached to the body portion 51 and to the machine frame.

The function of the improved positioning device is exactly the same as the dog 500 in the above mentioned McCabe patent. The length of the chain 60 is sufficient so that during the first step of the flanging operation the rack is permitted to move through its entire stroke, the collar 380 passing by the nose 61 as the latter is in a horizontal or inoperative position. After the last increment of the first step of the flange has been turned down and the rack is in an extended position, the handle 290 is thrown to the right, thereby disengaging the rack from the bender segment. Movement of the rack downwardly operates to cause the rotation of the body portion 51 of the device into a nearly vertical position through the tension 30 of the chain 60. This places the nose 61 in a position to engage the collar 380 when the rack is run back. The rack is now run back (while still disengaged) until the collar 380 strikes the nose 61. This operates to stop further movement of the rack. The rack is now re-engaged with the bender segment, and the tension on the chain 60 is thereby removed, so that the spring 55 operates to turn the positioning device to its inoperative position, in which the nose 61 is substantially horizontal. The second step of the flanging operation is now performed, the arc of oscillation of the bender being positioned so that at each stroke of the bender 45 the latter is returned clear of the flange. A similar series of operations occur when the rack is disengaged at the completion of the second step of the flanging operation.

After the last increment of the third step 50 of the flanging operation has been completed, and the rack is in an extended position, the body portion 51 of the improved device is manually rotated by a handle 59 into a vertical position. Provision is made 55 for retaining the device in this position, and for this purpose a latch pin 56 actuated by a spring 57 within the stop 54 is brought into engagement with a notch 58 in the end of the body portion 51. With the device, 60 locked in its vertical position with the nose 61 in the path of the collar 380, the rack is run back until the collar 380 engages the nose 61 thus returning the bender through an angle of approximately 30°. At this 65 point the bender is disengaged, again run

forward, reengaged and returned until the collar 380 again strikes the nose 61, returning the bender through a second angle of approximately 30°. It will be observed that the device is locked by the latch pin 56 in a vertical position during these first two steps of the return of the bender. After the bender has been returned through a second angle of approximately 30° the rack is disengaged, run forward and re-engaged. At 70 any time subsequent to the reengagement of the rack for the second time, the body portion 51 is moved by means of the handle 59 so as to disengage the notch 58 from the latch pin 56, thereby permitting the torsion 80 in the coil spring 55 to return the device to an inoperative position with the nose 61 substantially horizontal. As the rack is now returned, the collar 380 passes by the nose, thereby permitting the bender to be returned through an angle of approximately 85 40° and to its initial position.

While in the illustrated embodiment of the invention the oscillations of the bender are described as overlapping by an angle of 90 about 10°, it is to be understood that they may be caused to overlap by a different angle.

Having thus described the invention, what is claimed is:—

1. A flanging machine having, in combination, a driven member, a bender actuated thereby, a driving member capable of being moved into and out of engagement with the driven member to advance the bender step-by-step, means for actuating the driving member, and means for limiting the return movement of the driving member between the steps in the flanging operation subsequent to the first, including a member operatively connected with the driving member actuating means, and a device mounted upon said rod to rotate axially around the same and to engage a portion of the driving member when rotated into a predetermined position.

2. A flanging machine having, in combination, a driven member, a bender actuated thereby, a driving member adapted to be moved into and out of engagement with the driven member to advance the bender step by step, and a rotatable device adapted to be automatically rotated a certain amount into a normal operating position when the driving member is disengaged from the driven member between the steps in the flanging operation subsequent to the first, so as to be engaged by the driving member upon its return stroke to limit the same, and upon subsequent engagement of the driving member with the driven member to be automatically returned to an inoperative position so that movements of the bender are positioned to return the bender clear of the flange, said device having means whereby it is automatic- 115 120 125 130

cally locked in a position to be engaged by the driving member when rotated beyond its normal operating position.

3. A flanging machine having, in combination, a driven member, a bender actuated thereby, a driving member capable of being moved into and out of engagement with the driven member to advance the bender step-by-step, means for actuating the driving member, and means for limiting the return movement of the driving member between the steps in the flanging operation subsequent to the first, including a member connected with the driving member actuating means, a device mounted upon the member to rotate axially around the member, a spring cooperating with said device for urging it to rotate into a position out of engagement with the driving member, and means for rotating it into a position to be engaged by the driving member under predetermined conditions of operation.

4. A flanging machine having, in combination, a bender segment, a bender actuated thereby, a rack for actuating the bender segment adapted to be moved into and out of engagement with the bender segment to advance the bender step by step, power operated means for actuating the rack, power controlling means and a rotatable device cooperating with the power controlling means adapted to be automatically rotated a certain amount into a normal operating position when the rack is disengaged from the segment between the steps of the flanging operation subsequent to the first, so as to be automatically returned to an inoperative position when the rack is again engaged with the segment, whereby the oscillations of the bender are positioned to return the bender clear of the flange, said device having means whereby it is automatically locked in a position to be engaged by the rack when rotated beyond its normal operating position.

5. A flanging machine having, in combination, a driven member, a bender actuated thereby, a power operated driving member adapted to be moved into and out of engagement with the driven member to advance the bender step by step, power controlling means, and a rotatable device

cooperating therewith to position the movements of the bender between the steps in the flanging operation subsequent to the first so that the bender is returned clear of the flange, said device comprising a supporting rod, operatively connected with the power controlling means, a casing rotatably mounted on the rod and having an engaging nose adapted to engage a portion of the driving member when the casing is rotated into a normal operating position and to permit free movement thereof when the casing is rotated into an inoperative position, a spring for normally holding the casing in its inoperative position, a chain having one end attached to the casing and the other end attached to a fixed portion of the flanging machine and arranged to cause the casing to rotate into a normal operating position when the driving member is moved out of engagement with the driven member, a locking device adapted to lock the casing when the latter is rotated beyond its normal operating position, and means for manually disengaging the locking device to permit the casing to be rotated by the spring into its inoperative position.

6. A flanging machine having, in combination, a bender, means for actuating the bender, means for limiting the return movements of the bender actuating means to different lengths of movement comprising a member connected with the bender actuating means a rotatable device mounted upon said member to rotate axially around the same, a spring normally acting to hold the device in inoperative position, and means for locking the device in its operative position.

7. A flanging machine having, in combination, a bender, a bender segment carrying the bender, a rack for actuating the bender, means for disengaging the rack from the segment, means for limiting the return movement of the rack while disengaged from the segment comprising a member connected with the bender actuating means a rotatable device mounted upon said member to rotate axially around the same, a spring normally acting to hold the device in inoperative position, and means for locking the device in its operative position.

HUGH McCABE.
